CLAIM

The ornamental design for a base and cover for a vertical rotisserie, as shown and described.

DESCRIPTION

FIG. 1 is a perspective view of a base and cover for a vertical rotisserie showing our new design.

FIG. 2 is a front elevational view thereof, the rear being a mirror image.

FIG. 3 is a right side view thereof, as viewed in FIG. 2.

FIG. 4 is a left side view thereof, as viewed in FIG. 2.

FIG. 5 is a top view thereof.

FIG. 6 is a bottom view thereof.
